UNITED STATES PATENT OFFICE.

JOKICHI TAKAMINE, JR., OF NEW YORK, N. Y.

ICE OR WATER BAG.

1,264,710.

Specification of Letters Patent. Patented Apr. 30, 1918.

Application filed February 16, 1916. Serial No. 78,670.

To all whom it may concern:

Be it known that I, JOKICHI TAKAMINE, Jr., a subject of the Emperor of Japan, residing at New York, county and State of 5 New York, have made a certain new and useful Invention in Ice or Water Bags, of which the following is a specification.

The invention relates to ice or water bags.

The object of the invention is to provide 10 an ice or hot water bag, which is simple in structure and which, when applied to the portion of anatomy where hot or cold packs are required, will confine the heat or the coldness, as the case may be, to that particular portion.

A further object of the invention is to provide 15 a bag of the class described which will prevent the heat or coldness contained therein from diminishing due to radiation or other causes.

Further objects of the invention will appear more fully hereinafter.

The invention consists substantially in the construction, combination, location and 20 relative arrangement of parts, all as will be more fully hereinafter set forth, as shown in the accompanying drawing, and finally pointed out in the appended claims.

Referring to the drawings:

30 Figure 1 is a top plan view of a bag embodying my invention.

Fig. 2 is a view in elevation and in section taken on the line 2—2 Fig. 1, and looking in the direction of the arrows.

35 Fig. 3 is a top plan view of a modified construction embodying my invention.

Fig. 4 is a view in elevation and in section taken on the line 4, 4, Fig. 3, and looking in the direction of the arrows.

40 Fig. 5 is a bottom plan view of one end of the bag, shown in Figs. 3 and 4.

The same part is designated by the same reference numeral wherever it occurs throughout the several views.

45 In the ordinary hot or cold water bags, or ice bags, now used for sick room purposes, one great objection is that whether the bags are constructed of metal or rubber the heat or the coldness, as the case may be, quickly 50 loses its degree of effective temperature, due to radiation. Where hot applications are desired, only one portion of the bag comes in contact with the portion of the anatomy to which the bag is applied, and consequently the remaining surface of 55 the bag is free to radiate the heat there-

from, with the consequence that the water in the bag quickly loses its effective temperature, thereby necessitating frequent renewal of the hot water, and subjecting the 60 portion of the anatomy of the patient to frequent applications of varying temperatures, when the best results are obtained with continuous application of the same temperature. The same is true with respect to the 65 ice bag. The ice quickly melts, due to the surface of the bag being in constant communication with the air of the room.

In accordance with my invention, I obviate these and many other difficulties, by 70 employing a thermally sealed vessel of rounded contour, and with a flat bottom portion, preferably of rubber or other heat or cold conducting material.

In the drawing, 1 designates the outer 75 and 2, the inner walls of the vacuum space, 3, which walls are constructed of any suitable material and sealed air tight in any well known manner. Suitably secured to the wall 1 of the bag is a flat base or bottom 80 portion 4. This bottom portion may be of any suitable material, such as metal, rubber, or any temperature conducting material. I find it preferable to employ rubber for this purpose, as it admits a degree of 85 elasticity of the contact surface of the bag which enables the ready adaptability of the bag to practically any portion of the human anatomy, but my invention in its broad scope is not to be limited in this respect. 90

The thermally sealed rounded wall of the bag is provided with an opening, and neck portion preferably in the center thereof, as indicated at 5, over which may be secured or otherwise fastened, a cap or cover 6. 95

Thus it will be seen that when the bag is to be employed, say for hot applications, hot water is admitted therein through the neck or opening 5, and the cap 6 is screwed thereto. The bag is then applied to the 100 place where hot application is desired. The bag being thermally sealed, except at the bottom portion 4, none of the heat of the water can get out of the bag through radiation, conduction, or otherwise, except 105 through the bottom portion 4, which is in contact with the body of the user. Therefore all of the heat from the hot water is confined to the particular place where hot application was desired, and, as heat loss 110 has been completely eliminated the hot water retains its heat a very great length

of time. It will be understood that the same principle is involved where cold applications are required, and ice or cold water is supplied to the chamber 8 of the bag instead of the hot water.

If desired, buckle straps 9 and 10 may be provided, attached to the bag on opposite sides thereof, to allow the bag to be fastened to the body of the user, thereby preventing displacement by the movement of the user.

In the form of my invention shown in Figs. 3, 4, and 5, I eliminate the neck portion 5, and the cap or cover 6, and employ for the base or bottom portion some such material as rubber, water proof canvas, or other material, or combination of the same. In this form, the base 4, is fastened to the bottom of the curved vacuum wall 1 up to the point thereon indicated at 12. From this point the bottom portion 4, extends in the shape of a converging flap as indicated at 13. It will be seen that by this structure, an opening 14 is provided to the chamber 8, through which the hot water or ice, as the case may be, is admitted to the bag. When the bag is fitted for use, the flap 13, is pulled taut around the upper outer surface of the bag and secured thereto in any suitable manner. I show one simple arrangement for this purpose, wherein the end of the flap 13 is provided with a male clip 15, which fastens into a female clip 16, on the surface of the bag, as shown. Where rubber or other elastic material is employed

for the flap 13, a number of female clips 16, may be employed, as shown, to allow any degree of tautness desired or required to make the bag watertight.

While I have shown and described several specific arrangements embodying my invention, it will be understood that many different forms will readily suggest themselves to those skilled in the art without departing from the broad scope of my invention as defined in the claims.

Therefore, what I claim as new and useful and of my own invention, and desire to secure by Letters Patent, is,—

1. A bag for hot or cold applications comprising a concave side provided with heat insulating means, and a flexible heat conducting side.

2. A bag for hot or cold applications comprising a concave thermally sealed side, an elastic heat conducting side, and means for introducing material through the thermally sealed side.

3. A bag for hot or cold applications comprising a cup-shaped side composed of double walls confining heat insulating material and a flexible heat conducting side, whereby to prevent radiation from one side of the bag and to locally apply the heat conducting sides to conform to an irregular body, substantially as described.

In testimony whereof I have hereunto set my hand this 10th day of February, A. D. 1916.

JOKICHI TAKAMINE, JR.
